UNITED STATES PATENT OFFICE

EMMETT J. SCHUTT, OF RAMSEY, NEW JERSEY

COMBINATION TOOL

Application filed February 10, 1927. Serial No. 167,172.

My invention relates to new and useful improvements in a combination drawing, measuring, gaging, cutting, and magnifying instrument.

An object of my invention is to provide an instrument of more or less universal use that is adaptable to a pocket of the user.

A further object of the invention is to provide a combination tool or instrument of the protractor or bevel type having a ruler body and an arm pivoted thereto, with the body having beveled or inclined edges to which said arm may be swung in parallelism whereby parallel lines or measurements may be determined and obtained. A further object of the invention is to provide a protractor-like combination tool in which the pivoted arm is adjustable for engaging the points of twist drills, and which arm, when folded over the body, will conceal and house certain gage devices provided in the body. A still further object of the invention is to provide a protractor-like tool in which the pivoted arm constitutes a clip for engaging over the edge of the pocket in the garment of the user, said arm being formed to securely retain the tool within the pocket against accidental displacement.

The tool in part consists of a thin strip of material, preferably spring steel, having markings on both sides of standard units of measurement and their various subdivisions. One end of this strip is adaptable as a tack lifter or screw-driver, and the other end is provided with a magnifying lens and cutting point, other portions of this strip being utilized as a drill gage, a sheet metal gage, and a compass device. A pocket clip of novel construction is pivotally mounted on said strip and is adaptable as a protractor, T-square, bevel protractor, drill point gage, or a try-square. These and other uses are more minutely described hereinafter, reference being had to the accompanying drawings wherein:—

Fig. 1 is a plan view of the device with the pocket clip in its normal position.

Fig. 2 is a partial plan view of the device with the clip in use.

Fig. 3 is a bottom view of the device.

Fig. 4 is a side elevation of Fig. 1.

Fig. 5 is a vertical section on the line 5—5,

Fig. 2.

Fig. 6 is a vertical section on the line 6—6,

Fig. 2.

Fig. 7 is a vertical section on the line 7—7,

Fig. 1, and

Fig. 8 is a partial bottom view of the clip.

The body 10 consists of a thin rectangular plate, preferably of spring steel, having one of its ends 11 tapered and the extremity of said end beveled to a narrow chisel-like edge 12 for use as a paper cutter, screw-driver, or tack lifter. The other end is recessed to receive the lens-holder frame 13 consisting of a tubular section having a protruding portion 14 which tightly encircles the periphery of magnifying lens 15 and acts as a retainer therefor. The lower portion of said holder frame is flanged outwardly over the under side of the opening or recess in said body thereby retaining the lens and lens-holder assembly on the body. The extremity of this end of the body is provided with a small upturned flange 16, in which is placed a cutting point 17 to be used for various marking purposes.

The upper face of surface 18 of said body has a scale 19 preferably of inches and fractions thereof, marked upon it adjacent to the longer edge 19, the first inch containing small holes 20 which coincide with each graduation. In the other units larger holes 21 are provided but only on the inch marks. This series of holes, in conjunction with a compass point and pencil, converts this instrument into an accurate compass with an adjustable radius in every one sixteenth of an inch within range of the scale, which adjustment is accomplished by inserting a compass point through the desired small hole and the pencil in the desired larger hole thereby forming a beam-compass. This scale may, of course, be used for measuring or as a ruling edge, the latter use being facilitated by the edge 19 being under-beveled as shown in Fig. 7, thereby tending to eliminate blotting by the ruling edge.

The slots 22 corresponding in width to a

standard sheet metal gage are cut through the shorter edge 23. Each of these slots is indexed with its corresponding gage number marked upon the upper surface of the body 10, the portion of said body between said longitudinal edges 19 and 23 being drilled with holes 24 corresponding to standard twist drill and steel wire gage sizes, and each of these holes is indexed with its corresponding gage number. The tapered end of the body is provided with an inclined edge 25 connecting the shorter longitudinal edge 23 with the extremity edge 12, and said inclined edge is beveled to correspond with the bevel on edge 12, and said beveled surface being marked with two inch units divided into 32nds and 64ths respectively. This marking on a beveled surface will enable a very close measurement to be taken and the beveled edge may also be used as an envelop opener.

The pocket clip 26 is pivotally mounted adjacent one end by a rivet 27 in an approximately central position on the upper surface 25 of the body. The extremity of said pivoted end is provided with two beveled indicator points 28, which through correspondence with angle marks 29 will give a reading of the angle at which said clip or arm 26 is set 30 from 0 degrees to 90 degrees, both clockwise and counterclockwise from a position at right angles to edge 19. The extremity of the free end of said clip has a turned-up portion 30 to facilitate the entry of the clip over the edge of a pocket. The under side of this clip is provided with a nail file consisting of two slightly beveled file surfaces 31 and 32, the former being a fine file surface, the latter a rough file surface. When not in use the clip 40 is folded over onto the body 10, and portion 30 just clears lens holder 13 and serves as a guard for the lens.

The reverse side 33 of the body 10 is also utilized, the portion adjacent to edge 19 being marked with a decimal scale 34, having decimal subdivisions of inches from 10ths to 60ths inclusive. The portion adjacent the beveled edge 25 is provided with a metric scale 35 of millimeters and centimeters.

The uses to which a combination tool of this character may be placed are too numerous to be recited here. The turned-up portion 30 of the arm 26 not only facilitates the introduction of the pocket edge beneath said arm or clip but it provides a handle by which the clip or arm may be readily swung laterally from the body, as well as serving as a deflecting guard for the magnifying lens, and when the arm is in its folded position it covers and houses the drill gage openings. In grinding twist drills the angle made by the cutting edge and the drill axis may be checked by placing the edge 19 along the side of the drill and adjusting the protractor arm 26 so that its edge coincides with the

cutting edge of the drill. When the tool is arranged in the pocket the roughened under face of the clip or arm 26 secures the tool firmly against accidental dislodgment, and while the filing surfaces 31 and 32 have been 70 designated as being preferably for nail use, obviously they can be made of such character as to be used for filing metal of various descriptions. The extremity 12 provides a neat tack-lifting device especially designed 75 for draftsman's use.

It is understood that the standards and units of measurement and gages shown on this invention may be substituted for by other standards and units to suit other engineering or geographic conditions without altering the spirit of the invention.

I claim:

A combination tool or drafting instrument comprising a strip-like body having protractor markings thereon and having an opening therein, a lens arranged in said opening, and a pocket clip pivoted at one end to the body for swinging laterally to be used in co-operation with said body and markings 85 thereon as a protractor arm and having its free end extending outwardly adjacent the lens to protect the same and facilitate introduction of the pocket edge beneath the clip. 90
